Geo. N. Goddard Atty.

UNITED STATES PATENT OFFICE.

SILVIO AMOROSO, OF BOSTON, MASSACHUSETTS.

FOOT ACCELERATOR FOR MOTOR CARS.

Application filed June 11, 1926. Serial No. 115,382.

This invention relates to foot actuated accelerators for motor cars, and is particularly intended to provide a simple, economical and reliable device of this kind that is quickly and easily applicable to that type of motor cars which are furnished only with a hand lever control for regulating the carburettor in order that the carburettor may be controlled either by the hand or by the foot, without the one control interfering with the use of the other.

Generally speaking the invention comprises an attachment constructed and arranged to be easily applied to the usual connecting link extending from the rock-arm, adjacent to the steering post, to the carburettor, and having a flexible push or thrust member so connected with a foot plunger that when the thrust member or pusher is pushed down by the plunger it will transmit the thrust of the pedal to the connecting link and shift the regulating arm of the carburettor to open position against the opposing pressure of a return spring.

This improved attachment makes use of all parts of the existing type of motor car, is adapted to permit quick removal of the floor-board and itself affords an operative connection between the manually actuated rock-shaft and the link as well as a connection between the foot-actuated thrust member and said connecting link.

Other features of the invention will be particularly described in the following specification and will be defined in the claims hereto annexed.

In the accompanying drawings I have illustrated a simple, inexpensive and convenient form of the attachment forming the subject matter of the present improvement, in which:

Figure 1 is a plan view showing so much of the gas-regulating mechanism of a Ford car as is concerned with the present invention to which my foot accelerator attachment is applied.

Figure 2 is an enlarged detail view showing, in partial prospective, the application of this attachment to the rock-arm at the bottom of the gas-regulating rock-shaft.

Figure 3 is a detail view, partly in cross section, showing the slideable carriage joining the foot-actuated thrust member with the carburettor-actuating link.

Figure 4 is an end elevation showing the means for clamping the guard or sheath, surrounding the thrust wire, to the supporting and connecting arm on which the carriage is mounted.

Figure 5 is a plan view of the parts shown in Figure 4.

Figure 6 is a detail view showing the floor socket member which forms the bearing support for the foot plunger or button.

Ordinarily, as is well known to those familiar with Ford cars, an obliquely inclined rock-shaft or rod 2 is mounted adjacent to the steering post, shown in dotted lines in Figure 1, and is provided with a manual handle 2^a at its upper end, and with a rock-shaft 3 at its lower end into which is hooked a connecting link 4, which extends across the engine between the front and rear blocks 7, and is hooked into an eye in the carburettor-regulating arm 5, so that, according to the showing in Figure 1, a clock-wise rotation of the rock-arm 3 results in a counter-clockwise rotation of the regulator arm 5 of the carburettor 6, thus opening the carburettor for the delivery of gas to the engine to a greater or less degree.

This construction is made use of in the application of my present attachment in such manner as to make it possible to actuate the connecting link 4 either through the rock-arm 3, or through a plunger or button 19 mounted in the floor-board 1, of the motor car.

Instead of leaving the connecting arm 4, with its hook end 4^a, hooked into the aperture in the rock-arm 3, I remove this end of the link from the rock-arm and hook it into a sliding carriage 10 which is slidably mounted on one arm 9 of a bent or double rod, whose other arm *a* is provided with a hook-end 8^a to hook into the aperture in the rock-arm 3, into which the hook-end 4^a of the connecting link is hooked when no foot attachment is used. This bent arm 8, 9, therefore, is supported by the rock-arm 3 and itself forms the support of a sliding carriage 10.

On the upper side, the sliding carriage is provided with a clamping plate 11, having a concave clamping jaw 11^a, matching with a clamping jaw 10^a, formed on the carriage 10. The clamping plate is clamped firmly to the carriage 10 by means of a clamping screw 12 so that the jaws 10^a and 11^a, on

the one side, firmly grip the inserted portion of the connecting link 4. On the other side of the carriage the clamping plate 11 clamps the end of a wire 20, which forms 5 a flexible thrust member or pusher which, by pressure of the foot, exerts an endwise thrust against the sliding carriage by reason of its clamped engagement with the carriage, just described, so as to force the carriage 10 against the pressure of the extensible 10 return spring 10^c to slide toward the left of the driver, carrying with it, necessarily, the connecting link 4 which is clamped to the carriage, and whose bent end or hook 15 4^a rests in a receiving aperture formed in the carriage.

A slender wire, such as a piano wire or the like, particularly in a curved position, would easily buckle under the downward 20 endwise thrust of the foot plunger 18. To avoid this, therefore, I provide a hollow cable or sheath 25 whose upper end is clamped securely to the lower end of a tubular socket member 16 attached to the floor- 25 board 1 of the car, while the lower end of said sheath or guard is clamped firmly to the double end of the supporting rod 8, 9, by means of a pair of clamping plates 21, 22, and a clamping screw 23.

30 It will be understood that the thrust wire 20 is free to slide inside this sheath and projects out of and beyond the lower end of the sheath for clamping attachment to the carriage 10, as already described.

35 The upper end of the thrust wire 20 is carried into the sleeve 16, and is there attached to a plunger 18, which is provided with a removable head or button 19 for distributing the pressure against the sole of 40 the foot, said head being provided with a threaded shank 19^a to removably secure it to the end of the slideable plunger 18.

The socket or sleeve 16 is provided, intermediate of its ends, with an oblique attaching flange 16^a, so that it may be secured to the floor-board by means of a screw 16^b which is accessible from the top of the floor-board. This construction makes convenient provision for the quick removal of the floor- 45 board and the quick re-assemblage of the actuating plunger and its socket, since all that is needed, in order to remove the floor-board, is to unscrew the head or button 19 from the plunger, thereby allowing the 50 plunger to slip down out of the lower end of the sleeve as the floor-board is removed.

The plunger can be readily re-inserted when the floor-board is restored to normal position and the head or button 19 replaced on the upper end thereof. If desired the attaching screw 16^b may be removed so as to pull the floor-board away from the sleeve. Ordinarily this will not be necessary.

55 The operation of the device will be readily understood. Hand control of the carburet-

tor, through the rock-arm 3, and the link 4, is always available by reason of the fact that the link 4 is connected to the rock-arm permanently by means of the arm 8 and the carriage 10, to which the link is clamped. 70 On the other hand, without removing the rock-arm at all, the downward pressure of the foot on the plunger 18 pushes the wire downward and causes the carriage 10 to travel outwardly on the arm 9, against the 75 yielding pressure of the return spring. The sheath 25, while having sufficient flexibility to follow the necessary curvature to make the connection between the floor-board socket 16, and the attaching clamp 21, is sufficiently 80 strong to prevent the buckling of the wire. The only support needed for the attachment is that provided by the rock-arm 3, at the bottom of the floor-board, and socket 16 at the top. The mechanism is instantly 85 responsive to pressure on the plunger and can be very quickly applied to any car of this type.

What I claim is:

1. In a motor car accelerator, the combination with the carburettor throttle arm and its actuating link arranged to be actuated by a manually controlled rock arm, of a spring-pressed movable carriage, to which said link is connected, carriage-supporting means connected with said rock arm for support, a foot-actuated plunger mounted in the foot-board of the car, and a thrust transmitting wire connected at one end to said plunger and at the other end to said movable carriage 90 whereby the depression of the plunger pushes the carriage and the link against the resistance of the spring to throttle-opening position.

2. A foot actuated accelerator attachment 105 for a motor car provided with a manually controlled rock arm and throttle-actuating link, embracing in its construction a supporting frame adapted to be connected with such rock-arm, a movable carriage mounted 110 on said frame, said carriage having link-supporting and retaining means, a foot-actuated plunger, a throttle-transmitting wire whose ends are secured respectively 115 to the carriage and to the plunger, a spring normally acting to yieldingly oppose movement of said carriage to throttle-opening position, and means for guiding said wire when the wire is pushed endwise by the depression of the plunger.

3. An accelerator attachment of the class described, in claim 1, embracing a supporting frame comprising two arms, one of which is adapted to be connected to a manually controlled rock-arm, a carriage slideably mounted on the other arm of the frame against spring resistance, means for clamping a throttle-actuating link, to said carriage, foot-actuated means for pushing said carriage against the spring resistance to open 130

the throttle, said means comprising a foot plunger and a thrust wire forming operative connection between said plunger and the carriage, and an open ended enclosing sheath 5 confining said wire to prevent it from buckling.

4. An accelerator attachment of the class characterizing claim 1, embracing a frame having two divergent arms one of which 10 is adapted to be connected with the manually controlled rock-arm of the throttle mechanism, a slideable spring-pressed carriage on the other arm, means for securing the link of the throttle mechanism to said carriage, 15 a sleeve socket mounted in the foot-board of the car, a foot plunger mounted therein, a hollow sheath secured at one end to said sleeve and at the other end to the carriage-supporting frame, a thrust wire passed 20 through said sheath having one projecting end secured to the carriage and the other projecting end secured to the plunger.

5. In a device of the class described, the combination of a socket sleeve secured in the 25 foot-board of a motor car, a plunger mounted therein and provided with a quick detachable head to permit the removal of the foot-board without the plunger, a thrust wire secured to the lower end of said plunger 30 and having operative connection with the actuating link of the throttle valve of a motor car to force said link to valve-opening position while permitting said link to be independently actuated by a manually 35 controlled arm, and means for preventing

said thrust wire from buckling under the thrust of the plunger.

6. In a device of the class described, the combination of a plunger adapted to be mounted in the foot-board of a motor car, a 40 thrust wire secured to said plunger, means for operatively connecting said wire with the throttle-actuating link of the car, and means also connecting said link with a manually controlled rock-arm whereby the link 45 may be independently actuated by the rock-arm or by the thrust of the wire when actuated by the plunger, and a sheath arranged to surround the wire to prevent it from buckling under endwise pressure of the 50 plunger.

7. A foot accelerator attachment for a motor car, embracing a board bent to form two arms one of which is provided with a hook at its end, a carriage slidably mounted 55 on the other arm to move against the pressure of a helical spring mounted on said arm, means for securing a throttle-actuating link to the carriage, a curved tube secured at one end to said rod and having its other 60 end secured to a sleeve inserted in the foot-board of the car, a foot plunger mounted inside said sleeve, and a thrust-transmitting wire slidably mounted in said tube and having one end secured to the carriage to actuate it against the spring and its other end 65 attached to the plunger.

In witness whereof, I have subscribed the above specification.

SILVIO AMOROSO.
